(57) **CLAIM**

The ornamental design for a screwdriver tool box set, as shown and described.

DESCRIPTION

FIG. 1 is a first perspective view of a first element of a screwdriver tool box set showing my new design;

FIG. 2 is a second perspective view of the first element thereof;

FIG. 3 is a front view of the first element thereof;

FIG. 4 is a back view of the first element thereof;

FIG. 5 is a left side view of the first element thereof;

FIG. 6 is a right side view of the first element thereof;

FIG. 7 is a top view of the first element thereof;

FIG. 8 is a bottom view of the first element thereof;

FIG. 9 is a first perspective view of a second element of a screwdriver tool box set showing my new design;

FIG. 10 is a second perspective view of the second element thereof;

FIG. 11 is a front view of the second element thereof;

FIG. 12 is a back view of the second element thereof;

FIG. 13 is a left side view of the second element thereof;

FIG. 14 is a right side view of the second element thereof;

FIG. 15 is a top view of the second element thereof;

FIG. 16 is a bottom view of the second element thereof;

FIG. 17 is a combination view of the first element and the second element of the screwdriver tool box set thereof;

FIG. 18 is an exploded view of the screwdriver tool box set thereof; and,

FIG. 19 is an enlarged view of the selected portion 19 in FIG. 1.

The dash-dash broken lines shown in the drawings depict portions of the screwdriver tool box set that form no part of the claimed design. The dot-dash broken lines in FIGS. 1 and 19 illustrate the periphery of the enlarged views of the screwdriver tool box set and form no part of the claimed design. claim.

1 Claim, 19 Drawing Sheets
